UNITED STATES PATENT OFFICE.

HARRIET ETHEL KELMAN, OF SYDNEY, NEW SOUTH WALES, AUSTRALIA, ASSIGNOR TO WILHELM HUBERT PAUL BOLL, OF SYDNEY, NEW SOUTH WALES, AUSTRALIA, AND CHARLES CUTBUSH, OF KALGOORLIE, WESTERN AUSTRALIA, AUSTRALIA.

DESIGN FOR A DOLL.

53,450.

Specification for Design.

Patented June 17, 1919.

Application filed July 10, 1918. Serial No. 244,331. Term of patent 7 years.

To all whom it may concern:

Be it known that I, HARRIET ETHEL KELMAN, a subject of the King of Great Britain, residing at Sydney, in the State of New South Wales, Commonwealth of Australia, have invented a new, original and ornamental Design for Dolls, of which the following is a specification, reference being had to the accompanying drawing, forming part thereof.

I claim:—

The ornamental design for a doll, as shown.

HARRIET ETHEL KELMAN.
